Primary Examiner — Steven J Czyz

(57) CLAIM

The ornamental design for a makeup bag, as shown and described.

DESCRIPTION

FIG. 1 is a top perspective view of a makeup bag, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a closed state view thereof.

The broken lines in the drawings illustrate the portions of the makeup bag, which form no part of the claimed design.
